UNITED STATES PATENT OFFICE.

MERRITT RICE, OF COLCHESTER, ILLINOIS.

METHOD AND DEVICE FOR PRODUCING PLATES FOR ARTIFICIAL TEETH.

1,343,935.

Specification of Letters Patent. Patented June 22, 1920.

Application filed October 9, 1919. Serial No. 329,581.

To all whom it may concern:

Be it known that I, MERRITT RICE, a citizen of the United States, residing at Colchester, in the county of McDonough and 5 State of Illinois, have invented a new and useful Method and Device for Producing Plates for Artificial Teeth, of which the following is a specification.

The present invention relates to dentistry 10 and has particular reference to a new method and device for producing plates for artificial teeth.

Experience has taught that patients who have lost the upper or lower sets of teeth 15 or both or part of either set cannot fully control the muscles of the jaw to the extent of causing the upper and lower gums to strike. Thus, the "bite" obtained in the wax or plaster cast ordinarily used is im- 20 perfect and the plates made therefrom are not the exact likeness of the patients' gums, consequently they do not fit accurately and are uncomfortable.

With the above in mind, it is the prin- 25 cipal object of the invention to enable the patient to fully control these muscles, thereby obtaining a perfect "impression" or "bite" so that a true plate or plates may be made therefrom.

30 A further object of the invention is to produce accurately fitting plates for artificial teeth through the medium of trial plates or dies substantially the same size and shape of the patient's gum, upon one face of which is disposed a wax or plaster bite in which the impression of the gum is obtained, and upon the opposite face of which teeth project that mate with and contact with the teeth opposite the gum being fitted; in 35 the case of both gums being fitted a pair of these dies are used one for each gum, the teeth of which abut when the mouth is firmly closed thereby producing an accurate impression in the "bites."

40 Another object of the invention is to institute a method and device for producing plates for artificial teeth wherein the wax model of the patient's gum will not disturb or distort the shape of the denture upon 45 removing the model from the denture.

An additional object of the invention resides in the provision of a method and device of the above character which is simple to perform, is labor saving, and which will 55 render the finished plates accurate and comfortable.

With the above objects in view the invention consists of the various steps as herein-after set forth and claimed.

In the drawing:

Figure 1. is a plan view of the die having the blank plastic bite in position therein, part of the bite being broken out;

Fig. 2. is an elevation illustrating the die in the person's mouth, the upper row of 65 teeth being patient's natural teeth which coincide with the teeth carried by the die;

Fig. 3. is a transverse sectional view of the die after impression has been formed in the plastic bite in the latter shown in 70 Fig. 2;

Fig. 4. is made from the die after the im- 75 pression or bite has been obtained;

Fig. 5. is a bottom plan view of the die, parts being broken away to illustrate the 5 matrix or wax bite;

Fig. 6. is a view illustrating a pair of dies, one for each gum;

Fig. 7. is a view of the die for the lower gum, partly in section, partly in elevation, 80 in position on the denture;

Fig. 8. is a side elevation of the denture.

In carrying out the invention there is pro- 85 vided a plate or die 5 having its inner face concaved or recessed as indicated at 6 and 90 projecting from the opposite face thereof is a set of artificial teeth 7. A pliable wire or other reinforcing element 8 extends longitudinally within the plate 5. This plate is formed from a soft pliable substance such 95 as wax or the like so that the plate may be readily adjusted to the person's gum by bending the same to the proper degree. A number of these plates constitute a set, each plate being of a different size.

A wax body or bite 9 is arranged in the recess 7 and extends the length of the plate, this bite or matrix being softer than the die or plate or the plate being slightly harder than the bite or matrix. After the impres- 100 sion is made in the bite and a model or denture made therefrom it is removed so that the plate or die may be used again.

The method is reduced to practice in the following manner:

First, the blank wax body is placed in the recess in the plate and the plates placed in the patient's mouth with the blank body against the alveolar ridge of the gum; sec- 110 ond, the plate is shaped to the gum by press- ing the same with the fingers until the teeth carried by the plate are disposed in mating

relation to the natural teeth; third, the patient now closes the mouth bringing the teeth on the plate and the natural teeth firmly together to cause an impression of the gum to be made in the wax body 9; fourth, the plate with the impressions in the wax bite is removed from the gum and the denture made therefrom, from which the permanent plate is fashioned in the usual manner. In the case of both sets of teeth being missing, a pair of plates are arranged against the gums as above stated in coinciding relation, and the process carried out as set forth.

15 I wish to here state that I do not limit myself to the exact steps of the method as outlined but that changes may be resorted to without departing from the scope or spirit of the invention, and further that, I am only 20 limited by the appended claims.

What is claimed is:

1. The method of obtaining impressions, in the manufacture of artificial teeth plates, consisting of placing a plastic coated die of 25 hardened wax provided with a set of teeth, upon the gum and arranging the same to coincide with the teeth on the opposite gum; the impression being obtained in the plastic coating upon firmly biting the sets of teeth 30 together.
2. The method of obtaining an impression, in the manufacture of plates for artificial teeth, consisting of applying a blank bite of soft wax to a die of pliable wax 35 harder than the bite provided with a set of teeth, placing the die on the gum so that the teeth are disposed in mating relation to the teeth of the opposite gum, the impression being formed in the bite upon biting the 40 teeth together firmly.
3. The method of obtaining an impression, in the manufacture of artificial teeth consisting of first forming a die of substantially 45 the shape and size of the alveolar ridge of the patient's gum, second apply a

matrix thereto, third, placing the whole in the patient's mouth with the matrix against the alveolar ridge of the gum, and fourth, allow the patient to bite so that an impression of the gum will be formed in the 50 matrix.

4. The method of obtaining an impression in the manufacture of artificial teeth consisting of forming a die of pliable material and fixing a set of teeth thereon, second applying a matrix thereto, third, placing the whole in the patient's mouth with the matrix against the alveolar ridge of the gum, and fourth, allowing the patient to bite so that an impression of the gum will be formed in 60 the matrix.

5. As an article of manufacture a plate of a shape to conform to a person's alveolar ridge and provided with a row of artificial teeth, a plastic body supported therein in 65 which the impression of the gum is obtained upon engaging the teeth on a plate with the teeth upon the opposite gum.

6. As an article of manufacture, a plate of a shape to substantially conform to the patient's alveolar ridge and formed of a pliable material to enable the plate to be molded around the gum, a row of artificial teeth projecting from one edge of the plate and adapted to abut the teeth upon the opposite gum upon closing the jaws, and provided with a recess in its opposite face that extends the entire length thereof, a bendable element extending longitudinally within the plate, and a matrix disposed within the recess in which the impression of the gum is obtained upon applying pressure thereto by manipulating the jaws.

In testimony that I claim the foregoing as my own, I have hereto affixed my signature 85 in the presence of two witnesses.

MERRITT RICE.
